PRESETTING INTERVAL TIMER OR SIMILAR
ARTICLE

Thomas G. W. Nevell, Riverside, Conn., assignor
to The FR Corporation, New York, N. Y., a cor-
poration of New York

Application June 11, 1949, Serial No. 3,212

Term of patent 14 years

(Cl. D42—7)

To all whom it may concern:

Be it known that I, Thomas G. W. Nevell, a citizen of the United States, and a resident of Riverside, in the county of Fairfield, State of Connecticut, have invented a new, original, and ornamental Design for Pre-setting Interval Timer, or Similar Article, of which the following is a specification, reference being had to the accompanying drawing, forming a part thereof, in which:

Figure 1 is a front elevational view of a pre-setting interval timer, or similar article, showing my new design;

Figure 2 is a side elevational view thereof; and
Figure 3 is a top plan view thereof.

I claim:

The ornamental design for a pre-setting interval timer, or similar article, as shown.

THOMAS G. W. NEVELL.
